UNITED STATES PATENT OFFICE.

MELVIN W. COTTLE, OF ST. LOUIS, MISSOURI, ASSIGNOR TO ALLEN STEAM TRAP AND SEPARATOR COMPANY, OF ST. LOUIS, MISSOURI, A CORPORATION OF MISSOURI.

STEAM-TRAP.

SPECIFICATION forming part of Letters Patent No. 731,756, dated June 23, 1903.

Application filed July 21, 1902. Serial No. 116,381. (No model.)

To all whom it may concern:

Be it known that I, MELVIN W. COTTLE, a citizen of the United States, residing at St. Louis, Missouri, have invented a certain new and useful Improvement in Steam-Traps, of which the following is a full, clear, and exact description, such as will enable others skilled in the art to which it appertains to make and use the same, reference being had to the accompanying drawings, forming part of this specification, in which—

Figure 1 is a central vertical sectional elevation. Fig. 2 is a detail, and Figs. 3, 4, 5, and 6 are diagrammatic views illustrating the operation of the device.

My invention relates to improvements in steam-traps, my object being to provide a simple and efficient structure in which the discharge-pipe for the water is closed by a water seal, thus preventing escape of steam from the said trap.

To these ends and also to improve generally upon devices of the character indicated my invention consists in the various matters hereinafter described and claimed.

Referring now more particularly to the drawings, 1 represents a suitable casing, and 2 refers to an inlet-pipe opening into the top of the same for leading the water and steam to the casing-chamber. A suitable guide-post 3 extends upwardly from the bottom of the casing, and a cup 4 has an opening in its bottom which receives a cupped part 4^a, whose pocket 5 receives the said guide-post, while the top of said cupped part forms a valve for the open end of the discharge-pipe, the said post being received sufficiently loosely in said pocket to permit free vertical movement of the cup. A spring 6, coiled about the post, bears between the under surface of the cup-bottom and suitable adjusting-nuts 7 upon the threaded lower portion 8 of the said post, the said cup being thus yieldingly maintained in uppermost position. A deflector 9 is suitably secured to the casing below the inlet-opening and extends across the open upper end of the cup, whereby incoming water is caused to fall into the chamber of the casing and not into the cup.

50 A discharge-pipe 10 is suitably supported

in the casing above the bottom of the cup, said pipe extending vertically within said cup and having its lower end open and in line with the upwardly-projecting part 11 of the cup-bottom, which produces the recess 5 for 55 the guide-post. A substantially horizontal pipe 12 connects the lower portion of the casing-chamber with the vessel into which the water is to be discharged, said pipe being provided with two valves 13 and 14, and from a 60 point between the said valves a pipe 15 connects the pipe 12 with the upper portion of the vertical pipe 10.

The pipe 10 can of course be supported in many ways; but I have here shown this 65 pipe as depending from a spider 16, supported upon the walls of the casing. The pipe 10 is merely a pipe-section open at both ends, the upper end being closed by means of a cap-plate 17, fastened upon the spider. 70

The cup 4 is normally maintained in raised position by means of the spring 6, and the projecting portion 11 of the cup-bottom enters the open lower end of the discharge-pipe and closes the same. When sufficient water 75 has been discharged into the casing-chamber to rise above the upper edge of the cup, this water overflows into said cup and surrounds the lower portion of the discharge-pipe 10. When the cup has received a sufficient amount 80 of water to overcome the force of the spring, the cup falls, thus carrying the portion 11 (which is, in effect, a valve) away from the end of the discharge-pipe and opening said pipe. The steam above the water then forces 85 water from the cup until such an amount has been discharged that the weight of the contained water is overcome by the force of the spring, whereupon the spring again raises the cup and forces the valve into position to close 90 the discharge-pipe, the cup remaining in this elevated position until sufficient water has flowed thereinto over its upper edge to overcome the force of the spring. The parts are so proportioned and arranged that the cup 95 does not receive sufficient water to lower the same until the water in the cup has risen a considerable distance along the discharge-pipe and the cup is re-elevated to cause its valve to close the discharge-pipe before the 100

cup has been emptied to such extent that the water remaining in the cup is below the lower end of the discharge-pipe. Thus the discharge-pipe is closed to the passage of steam at all times, the valve 11 normally maintaining the pipe closed and the water in the cup closing the pipe to the passage of steam during the time that the valve 11 is removed from the discharge-pipe against the action of the spring 6.

Normally the valve 13 is closed; but when it is desired to flush the casing-chamber for cleaning purposes or otherwise this valve can be open and the chamber can be flushed in a well-understood manner.

The construction of the present device prevents movement of the cup and its valve at too frequently recurring intervals, thus saving the parts from unnecessary wear. The water is usually fed by drops from the steam-separator to the trap, and the deflector causes the water to discharge into the casing and not directly into the cup. When the water in the casing has reached the level of the upper edge of the cup, it overflows into the latter, as shown in Fig. 3, and this overflow continues without causing any operation of the parts until the cup has received such an amount of water (e. g., the amount shown in Fig. 4) that the force of the spring is overcome, when the cup falls and permits a portion of its contained water to discharge through the pipe, as shown in Fig. 5. The spring then reasserts itself and elevates the cup, thus closing the outlet-pipe and raising the upper edge of the cup above the level of the water in the casing, as shown in Fig. 6. Therefore before a second lowering of the cup can occur such an amount of water must be deposited into the casing that first the water-level in said casing is raised above the upper edge of the cup and then the water overflows into said cup.

I am aware that many minor changes in the construction, arrangement, and combination of the several parts of my device can be made and substituted for those herein shown and described without in the least departing from the nature and principle of my invention.

Having thus described my invention, what I claim as new, and desire to secure by Letters Patent, is—

1. In a steam-trap, a casing, an outlet-pipe, a movable cup receiving the open inner end of said pipe, a valve for said opening, connected to and movable with said cup, adapted to close said opening, means for holding said cup normally elevated, an inlet-pipe opening into said casing at its upper end and a dome-shaped deflector of greater diameter than said cup, below said inlet adapted to cause water entering the casing to fall outside of the cup; substantially as described.

2. In a steam-trap, a casing, an outlet-pipe, a movable cup receiving the open inner end of said pipe, a valve for said opening, con-

nected to and movable with said cup, adapted to close said opening, means for holding said cup normally elevated, an inlet-pipe opening into said casing at its upper end, and a dome-shaped deflector of greater diameter than said cup, connected with and supported by said casing below said inlet, adapted to cause water entering the casing to fall outside of the cup; substantially as described.

3. In a steam-trap, a casing, an outlet-pipe, a movable cup receiving the open inner end of said pipe, a valve for said opening, connected to and movable with said cup, adapted to close said opening, means for holding said cup normally elevated, an inlet-pipe opening into said casing at its upper end and a dome-shaped deflector of greater diameter than said cup, connected with and supported by said casing below said inlet, adapted to cause water entering the casing to fall outside of the cup; substantially as described.

4. In a steam-trap or the like, a casing, an outlet-pipe having its lower end open, a movable cup receiving the said open end of said pipe, a guide-post below said cup, and means for elevating said cup, a portion of the bottom wall of said cup being cupped upwardly to produce a valve for said pipe and a pocket for said guide-post; substantially as described.

5. In a steam-trap or the like, a casing, an outlet-pipe provided with an opening, a movable cup receiving the portion of said pipe provided with said opening, means for elevating said cup, a guide-post below said cup, the bottom wall of said cup being provided with an opening, and a part in said opening and provided with a valve for said pipe-opening and a receiver for said guide-post; substantially as described.

6. In a steam-trap or the like, a casing, an outlet-pipe having an opening in its lower end, a movable cup receiving the said lower end of said pipe, a valve for said opening carried by said cup, a guide-post coöperating with said cup, and a spring coiled about said post and tending to elevate the said cup; substantially as described.

7. In a steam-trap or the like, a casing, an outlet-pipe provided with an opening, a movable cup receiving the portion of said pipe provided with said opening, a valve for said opening connected with said cup, a guide therefor, means for elevating said cup and holding the same in a normally elevated position, and a dome-shaped deflector connected with said casing below said inlet-pipe for deflecting water from said opening beyond the outer walls of said cup; substantially as described.

In testimony whereof I hereunto affix my signature, in the presence of two witnesses, this 8th day of July, 1902.

MELVIN W. COTTLE.
